DESIGN FOR A TOY SHIP

Willy Kellermann, Nuremberg, Germany

Application November 29, 1932, Serial No. 46,194,
and in Germany October 7, 1932

Term of patent 3½ years

To all whom it may concern:

Be it known that I, WILLY KELLERMANN, a citizen of the Republic of Germany, residing at Nuremberg, Bavaria, Germany, have invented a new, original, and ornamental Design for Toy Ships, of which the following is a specification, reference being had to the accompanying drawing, forming part thereof.

The drawing illustrates in Fig. 1 a side view, in Fig. 2 a plan view and in Fig. 3 a front view of a toy ship showing my new design.

I claim:

The ornamental design for a toy ship as shown. In testimony whereof I affix my signature.

WILLY KELLERMANN.
